ROLL TOWEL CABINET

Andrew Falk, Homestead, Pa., assignor, by direct and mesne assignments, of one-third to Edward L. Hillenbrand and one-third to William Hillenbrand, both of Pittsburgh, Pa.

Application December 31, 1934, Serial No. 759,833

20 Claims. (Cl. 312—38)

My invention relates to a cabinet for holding a continuous or roll towel and dispensing lengths thereof to successive users.

Roll towel cabinets as heretofore constructed have embodied a pair of friction driving rolls operating upon the used and unused portions of the towel respectively, and effective to roll up the former as the latter is manually pulled off the roll in which it is supplied, the friction driving rolls being connected by a chain and sprocket drive. A loop of the towel hangs below the cabinet at all times. These devices are objectionable, first, from the standpoint of appearance, since the soiled or used portion of the towel is always visible to the subsequent users, who must pull out a fresh supply of toweling for their own use. Another objection is that it is very difficult to synchronize the friction roll drive. As a result, the length of the loop of towel hanging below the cabinet varies from a minimum, which makes it difficult to use the towel, to a maximum, which is very unsightly. In addition, the wear on the moving parts, particularly the friction driving rolls, is not uniform at all points.

I have invented a roll towel cabinet which overcomes the above-mentioned objections and, furthermore, provides a much more effective means of holding and dispensing continuous or roller towels than has been available heretofore so far as I am aware. In accordance with my invention, I use a single friction driving roll to operate the roll of used towel. This pulls fresh towel from the unused roll. In addition, I provide a door adapted to be opened by the means for operating the friction driving roll. The door is closed automatically after the section of towel exposed thereby has been used and released. Other advantages characterizing my invention will become apparent as the description proceeds and the novel features thereof will be particularly pointed out in the appended claims.

A complete understanding of the invention may be readily obtained by consideration of the accompanying drawings read in connection with the following description. In the drawings, illustrating a present preferred embodiment of the invention:

Figure 1 is a front elevation showing my invention;

50 Figure 2 is a sectional view thereof taken on the line II—II of Figure 1;

Figure 3 is a front elevation with the front wall removed and parts in section;

55 Figure 4 is a sectional view taken along the line IV—IV of Figure 3;

Figure 5 is a partial front elevation showing means for preventing access to the towel until the proper time;

Figure 6 is a similar view after the access-preventing means has been withdrawn; 5

Figure 7 is a sectional view similar to Figure 2 with the parts in operated position and the towel withdrawn from the cabinet for use;

Figure 8 is a sectional view along the line VIII—VIII of Figure 3; and 10

Figure 9 is an elevation of the interior of a portion of the front wall of the cabinet.

Referring now in detail to the drawings, a cabinet 10 has a front wall composed of hinged sections 11 and 12 and a fixed, sloping section 15 15 13. Side walls 14, a rear wall 15, and a suitable top and bottom complete the cabinet. The top is provided with a hinged cover 16.

Frame side plates 17 and 18 (Figure 3) are secured within the upper part of the cabinet in 20 any convenient manner. Slots 19 in the frame plates provide bearings for a roll 20 on which the fresh towel, indicated at 21, is supplied from the laundry. A plate 22 hinged to the top of the cabinet bears on the roll 21 and serves as a 25 brake to prevent overrunning of the coil of towel when unwound by means to be described later. Notches 23 in the side frame plates 17 and 18 are provided for receiving the roller 20 temporarily during installation and threading. 30

As shown in Figure 2, the towel 21 passes downwardly of the front wall of the cabinet over a gripper bar 24. This bar is carried on a yoke 25 hinged to the side frame plates. The yoke 25 normally rests on a cross bar 25'. The gripper bar itself is covered with a suitable friction gripping material for a purpose which will appear later. A cooperating friction gripping bar 26, similarly covered, is mounted at the bottom of a vertically sliding door 27. The door 27 moves in guides 28 secured to the interior of the upper hinged portion 11 of the front wall of the cabinet. The mounting of the door 27 in its guides may best be observed in Figure 9. The door 27, when lowered, closes an opening 29 in the hinged wall-portion 11. The upper portion of the latter may conveniently be provided with a mirror 30. A roller 31 is journaled in the lower edge of the opening 29 for a purpose which will become apparent later. 40

As shown in Figure 9, the door 27 has a rearwardly projecting finger 32 at one side thereof. This finger is adapted, when the hinged wall-portion 11 is closed, to enter a slot in a laterally extending plate 33 carried by a vertically recipro- 45 50 55

cable rack bar 34 (see Figures 2, 7 and 8). The rack bar 34 slides in guides 35a secured to the right-hand side wall 14 of the cabinet. It will be apparent that the door 27 is raised to uncover the opening 29 when the rack bar 34 moves upward.

Upward movement of the rack bar 34 is obtained by rotation of a driving gear 35 rotatably mounted on the right-hand side wall 14, as shown in Figures 2, 7 and 8. An operating lever 36 on the outside of the cabinet is connected to the gear 35 and movement of the handle thereon turns the gear to shift the rack bar 34 vertically. A counterbalancing rack bar 37 is vertically slideable in guides 35' fixed to the right-hand side wall 14 adjacent the rear wall 15.

Operation of the hand lever 36 also effects the advancement of a fresh portion of the towel 21 from the unused roll into position for access through the opening 29 when the door 27 is raised to open position. The gear 35 drives a pinion 38 which is similarly journaled on the inside of the right-hand side wall 14 of the cabinet. This pinion meshes with a pinion 39 which is likewise journaled on the inside of the cabinet. A friction driving roll 40 is journaled in the side frames 17 and 18 coaxially with the pinion 39. A pawl 41 carried on a plate 42 mounted on the pinion 39 cooperates with a ratchet wheel 43 keyed to the friction roll shaft 44. Slots 45 in the side frames provide bearings for a roll 46 on which the used portion of the towel indicated at 47 is wound. Notches 45', similar to those shown at 23', provide temporary supports for the roll 46 to facilitate threading of the towel. As will be apparent from Figures 2 and 7, the roll 46 rises in the slots 45 as the coil of used towel builds up thereon. As shown in Figures 2 and 7, the continuous towel is threaded over guide rolls 48 and 49 and around a roll frame 50 which is vertically slideable on guides 51 in the lower portion of the cabinet. The roll frame 50 has pins 52 adapted to enter slots 53 in the guides 51. A guide roll 54 is journaled in the frame. The slots 53 are vertical in their upper portion but toward the bottom of the cabinet have a forward inclination terminating in an enlargement 54a with a stop shoulder 55 adjacent thereto. The guide roll 54 is journaled in a plane rearwardly of that in which the axes of the pins 52 lie. The purpose of this construction is to prevent the frame 50 from rising when the friction roll 40 is operated to drive the coil 47. It will be apparent from Figure 2 that if torque is applied to the coil 47 to exert an upward pull on the rearward run of the towel, the frame 50 will be raised only slightly until the lower pins 52 engage the shoulders 55. Further rotation of the coil 47 will pull the soiled towel around the roll 54 and cause fresh towel to be advanced from the unused portion 21 to a position between the door 27 and the frame 50.

By now it will probably be apparent that when the lever 36 has been operated to open the door 27 and advance fresh towel into a position such that it is available through the opening 29, the user may seize the towel which will then appear as in Figure 6, and withdraw it in a loop as indicated in Figure 7, for use. As the loop of towel is pulled out, the towel is drawn over the roller 31 journaled in the lower edge of the opening 29. Withdrawal of the loop of towel causes the frame 50 to rise. It had already been explained that a pull on the rearward run of the towel locks the frame against upward movement. Similarly,

a pull on the front run of the towel will swing the lower part of the frame forward about the upper pins 52 as an axis so that the lower pins 52 clear the shoulder 55 to permit the frame to rise to the position shown in Figure 7 as the loop of towel is withdrawn.

Returning now to the door 27, a few additional details thereof improve the functioning of the apparatus. In the first place, the gripper bar 26 cooperates with the bar 24 when the door 27 is raised, as shown in Figure 7, to frictionally grip the towel tightly and prevent more towel from being pulled from the unused coil 21, as long as the door 27 is raised. The towel is engaged between the bars 26 and 24 before the door has reached the upper limit of its movement. The bar 24 then moves upwardly a short distance with the bar 26, the towel being gripped therebetween. Since these gripping bars are not effective until the door is fully raised, I provide a collapsible grille 56 (Figure 9) which is adapted temporarily to bar access to the towel, as shown in Figure 5. The grille 56 is extended by means of a hook 57 pivoted to the door 27 and adapted to engage the top bar of the grille. The grille is thus extended as the door is raised. A cam plate 58 (Figures 2 and 7) on the side frame 18 cooperates with the upper portion of the hook 57 to trip the latter and release the grille when the door 27 has reached its uppermost position in which the towel is tightly gripped between the bars 24 and 26.

The door 27 is also provided with a holding lug 59 (Figure 9). The means for engaging this lug to hold the door in elevated position during use of the towel will be described shortly. The upper edge of the door 27 is adapted to engage behind a finger 60 fixed to the hinged section 11 (Figure 3) to prevent opening of the latter when the door 27 is raised and the lever 36 in the operated (i. e., not the normal) position. The purpose of this will be explained later.

The door 27 also has a lock bar 61 cooperating with a slot 62 in the right-hand guide 28, as viewed in Figure 9. By advancing the bar 61 before closing the upper hinged portion 11 of the front wall, further operation of the device is prevented. This is useful in case it is desirable, for any reason, to suspend operation of the device.

Reverting to the drive mechanism for advancing fresh towel, I incorporate therein means for preventing "pumping" of the towel by short back and forth movements of the lever 36 between the extreme limits of such movement. This means includes a pawl 63 cooperating with the gear 35. The pawl is so shaped as to permit counterclockwise rotation of the gear as viewed in Figure 8, but to prevent clockwise rotation thereof. As the gear 35 turns counterclockwise, therefore, the pawl 63 rides over the gear teeth. It is thus impossible to reverse the gear 35 until a full angular movement hereof has been made. At that time, a cam 64 on the gear 35 raises the pawl 63 which is then latched by a pivoted detent 65. The gear 35 is thus freed for reverse movement. On completion of the latter, a finger 66 also secured to the gear 35 actuates the detent 65 to release the pawl 63.

As the door 27 is raised, the holding lug 59 displaces and slips past a detent 67 (Figure 4) pivoted on the inside of the left-hand side wall 14 of the cabinet. The door 27 is thus held in elevated position until the detent 67 is withdrawn. The detent 67 has a rearward extension 68 adapt-

ed to cooperate with a cooperating detent 69 pivoted on a channel-shaped slide 70 through which the upper left-hand pin 52 of the frame 50 projects. The upper end of the slide 70 works 5 in a guide channel 71. When the loop of towel is pulled out, it causes the frame 50 to rise. On upward movement of the frame 50, the detent 69 is displaced by the rearward extension 63 of the detent 67. On downward movement of 10 the frame 50, resulting from the release of the loop of towel, the detent 69 engages the rearward extension 68 and trips the detent 67 from beneath the holding lug 59 whereby the door 27 is released and permitted to drop. A pull knob 15 72 is connected to the rearward extension 68 to permit manual operation of the detent 67 under certain circumstances to be mentioned later.

The operation of exchanging used towels for 20 fresh ones is relatively simple. When the end of the towel is unwound from the coil 21, and passes beyond the gripper bar 24, it obviously can be pulled out of the opening 29. The frame 50 thus may or may not be raised by the user of the last end of the roll. If not, the door 27 will 25 remain open and the lever 36 in operated position. If this happens, the attendant will first have to open the lower hinged portion 12 of the front wall and pull down on the knob 72 to close the door 27 because, as above stated, the upper 30 hinged portion 11 is locked by the engagement of the upper edge of the door behind the locking finger 69 when raised. When the door 27 has thus been closed, the lever 36 and the rack bar 34 then return to their positions illustrated in 35 Figure 8. This is a safeguard against the operator changing towels and closing the machine up ready for use with the lever 36 in operated position. If this were done, the finger 32 would not enter the slot in the plate 33 when the hinged 40 portion 11 of the front wall is closed and the door 27 would not be operated on subsequent restoration of the lever to starting position and advancement therefrom. While the drive would operate to feed fresh towel, the door 27 would 45 not open to permit access thereto.

By lifting the coil 47 of soiled toweling out 50 of the slots 45 and placing it temporarily in the notches 45', the last few feet of used towel can be rolled on the coil and the latter then removed, the upper hinged wall-portion 11 having been 55 unlocked and opened. The roll 20 may then be placed in the notches 45' and a coil of fresh towel on its roll is then temporarily supported on hinged arms 73 having notches in their ends, which may be swung outwardly as shown in Figure 7 after opening the wall-portion 11. Towel is then threaded under the guide roll 48 and over the roll 49 and around the roll 54 of the frame 50. The end of the towel is then pulled up behind the front run and started around the roll placed in the notches 45'. When the roll 60 has been started, it is moved backwardly and downwardly in the slots 45 until it is engaged by the friction driving roll 40. The yoke 25 and the plate 22 may then be swung upwardly and the roll having the coil of fresh towel thereon deposited with its ends in the slots 19. The device is then ready for operation on closing the hinged wall portions 11 and 12, providing that the lever 36 is in the illustrated position when 65 the wall portion 11 is closed. As explained above, this is effected automatically since it is necessary to close the door 27 before the wall-portion 11 can be opened and the closing of the door 27 restores the lever 36 to the illustrated position. A finger hole 74 in the side frame plate

18 facilitates the manual disengagement of the pawl 41 from the ratchet wheel 43 so that the friction driving roll 40 can be manually turned to start the leading end of the fresh towel on its roll. This operation of the pawl disconnects the 5 friction driving roll from the drive mechanism normally employed including the lever 36 and associated gearing.

It will be apparent from the foregoing description that the invention provides a great improvement over towel cabinets known heretofore since it includes means for dispensing precisely a predetermined length of towel on each operation of the handle and always maintains the used towel concealed. The fresh towel is locked against excessive withdrawal when the door is open and access to the towel is prevented until the door is fully opened. Pumping of the towel is prevented. The exchange of fresh towels for soiled ones is relatively simple. The entire structure, furthermore, is simple in arrangement and relatively inexpensive to manufacture. The simplicity of the structure also contributes to easy maintenance. The apparatus may be embodied, as shown herein, in a cabinet adapted for wall mounting or may 25 equally well be disposed in a cabinet adapted to stand on the floor. Suitable shock absorbers for the moving parts may be used to limit the noise and jar so that the device is adapted for use in all locations even those such as hospitals where noise is objectionable. On operating the device only 30 fresh towel is exposed. The door which opens to expose the towel is locked in the open position until the towel has been pulled out and released 35 so that even if the door should be opened and the towel unused, only fresh towel would be visible. Pulling out the towel to any extent will cause the door to be closed when the towel is released. Only one friction driving roller is employed and chain drives are eliminated. The friction drive roll, 40 as well as the gripper bars, may be covered with abrasive cloth, rubber or other suitable frictional material. The invention is readily adapted to coin-controlled operation but the specific type of 45 coin-controlled release is largely a matter of choice and is, therefore, not described herein. The cabinet is economical in the use of towel because only a predetermined amount can be advanced on one operation of the lever.

Although I have illustrated and described herein only one form of the invention, it will be apparent that numerous changes in the described embodiment may be made without departing from the spirit of the invention or the scope of the appended claims.

I claim:

1. In a towel cabinet, means for supporting a coil of fresh towel, means for winding up the towel as used, vertically reciprocable means for maintaining a loop of towel of predetermined length therebetween, and means effective to prevent movement of said second-mentioned means only when the loop is tautened in response to operation of said first-mentioned means and not when the loop is pulled by a user.

2. In a towel cabinet, means for supporting a coil of fresh towel, means for winding up the towel as used, movable means for maintaining a loop of towel of predetermined length therebetween, 70 said second-mentioned means being movable by a pull on the towel extending therefrom to the fresh coil to feed a portion of the towel for use, and means preventing movement of said second-mentioned means when the towel extending from 75

the loop to the winding up means is tautened in response to operation of the latter.

3. In a towel cabinet, an opening through which a towel is accessible, manually operable means for advancing towel from a fresh coil thereof past said opening, means normally closing said opening and preventing access to the towel, means operable by said first mentioned means to operate said access preventing means and provide access to the 10 towel, means on said second mentioned means effective on complete operation of the latter to grip the towel extending from the fresh coil thereof to prevent manual unwinding thereof, and additional means for barring access to the towel 15 until the second mentioned means has operated completely and said towel gripping means is effective.

4. The apparatus defined by claim 3 characterized by means for rendering said access barring means ineffective when the means normally closing the opening has been fully operated.

5. In a towel cabinet, the combination with means for rotatably supporting a coil of fresh towel, a coiling roll on which used towel may be 20 coiled, means for feeding fresh towel and coiling used towel including only a single friction driving roll engaging the towel coiled on said coiling roll, of manually actuatable means for operating said friction roll, means for maintaining 25 a loop of towel of predetermined length between said coil and roll, and means whereby rotation of said friction driving roll solely and exclusively tensions said loop throughout its entire length 30 and pulls towel from said coil around said last-mentioned means.

6. In a towel cabinet, the combination with means for supporting a coil of fresh towel adapted to be made available for use in a loop of predetermined length, a roll for winding up the towel 40 as used, manually operable means independent of the towel effective to drive the roll to wind up used towel, vertically movable means for maintaining said loop of toweling of predetermined length between said coil and said wind-up means, 45 means for preventing movement of said movable means whereby rotation of said roll places the loop under tension throughout and pulls fresh towel from the coil, and means responsive to a pull on the portion of the towel extending toward 50 the coil of fresh towel, for rendering said movement-preventing means ineffective.

7. In a towel cabinet, the combination with an opening, a closure therefor precluding access to the towel in the cabinet, manually operable means 55 independent of the towel for drawing towel from a coil thereof past the opening, and opening the closure to expose the towel to be pulled out and used, means for locking the closure in open position, and means operable on release of the towel 60 for operating the last-mentioned means to release the closure and permit it to close said opening.

8. The apparatus defined by claim 7 characterized by means for gripping the towel to prevent it 65 from being pulled off the fresh coil.

9. The apparatus defined by claim 7 characterized by means for preventing used towel from being pulled back from said drawing means.

10. In a towel cabinet, an opening through 70 which the towel is accessible, means including a manually operable member for advancing fresh towel from a coil thereof past said opening, means normally closing said opening and preventing access to the towel, means operated by said member effective to operate said second mentioned 75

means and afford access to the towel, and means independent of the towel advancing means for holding in operated position the means normally closing said opening.

11. In a towel cabinet, an opening through 5 which the towel is accessible, means for advancing fresh towel from a coil thereof past said opening, a door normally closing said opening and preventing access to the towel, means operable with said first mentioned means to operate said 10 door to expose the towel, means for holding the door in open position, said holding means being operable by withdrawal of the towel from the cabinet and release thereof, for causing the release of said door whereupon it returns to its 15 initial position.

12. In a towel cabinet, a door normally barring access to the towel, an opening normally closed by the door through which the towel is accessible, and means including a member accessible on the 20 exterior of the cabinet and operable by a user, for opening said door and drawing fresh towel from a coil toward said door so as to be accessible therethrough, and means operated by the door for holding the door in open position to permit 25 access to the towel.

13. In a towel cabinet, a door normally barring access to the towel, an opening normally closed by the door through which the towel is accessible, and means including a member accessible on the 30 exterior of the cabinet and operable by a user for opening said door and drawing fresh towel from a coil toward said door so as to be accessible therethrough, means independent of said opening 35 means for holding the door in open position to permit access to the towel, means for normally maintaining a loop of towel adjacent said opening, and means moving with said loop-maintaining means and effective on release of the towel to render inoperative the door holding means.

14. In a towel cabinet, a door normally barring access to the towel, an opening normally closed by the door through which the towel is accessible, and means including a member accessible on the 40 exterior of the cabinet, operable by a user, and including a wind-up roll for used towel, for opening said door and drawing fresh towel from a coil toward said door so as to be accessible 45 therethrough, means for maintaining a loop of towel adjacent said door, and means for locking said 50 last-mentioned means against operation by the driving torque exerted on said wind-up roll.

15. A towel dispenser comprising a support for a coil of fresh towel, means for gathering the towel as used, retractile means for maintaining 55 a loop between the fresh and used towel, means frictionally engaging the used towel and effective to pull fresh towel from the coil thereof by tension thereon when said loop is maintained by said retractile means, a manually operable drive for said frictionally engaging means, means for preventing retraction of the loop-maintaining means, and means responsive to a pull on the portion of the loop extending toward the coil of fresh towel 60 to render ineffective said retraction-preventing means.

16. In a towel cabinet, means therein for supporting a coil of fresh towel, an opening in the cabinet through which the towel is accessible to a user, a door normally closing said opening, means including a member manually operable from the exterior of the cabinet, for drawing fresh towel from said coil past said opening and operating said door to expose the towel, and means including means operated with said door for locking the 75

fresh towel against further uncoiling thereof from said coil.

17. In a towel cabinet, means therein for supporting a coil of fresh towel, an opening in the cabinet through which the towel is accessible to a user, a sliding door normally closing said opening, means including a member manually operable from the exterior of the cabinet, for drawing fresh towel from said coil past said opening and 10 sliding said door back to expose the towel, and means including means operated with said door for holding the fresh towel against further uncoiling thereof from said coil.

18. In a towel cabinet, means therein for supporting a coil of fresh towel, an opening in the cabinet through which the towel is accessible to a user, a door normally closing said opening, means including a member manually operable from the exterior of the cabinet, for drawing fresh towel 15 from said coil past said opening and operating said door to expose the towel, a friction gripping bar on said door, and fixed means cooperating therewith when the door is open for holding the fresh towel against further uncoiling thereof from said coil.

19. In a towel cabinet, means therein for supporting a coil of fresh towel, an opening in the cabinet through which the towel is accessible to a user, a door normally closing said opening, means including a member manually operable 5 from the exterior of the cabinet, for drawing fresh towel from said coil past said opening and operating said door to expose the towel, and a friction gripping bar on said door, a relatively fixed friction gripping bar adapted to cooperate 10 with that on the door when the door is opened and seize the towel between them to prevent further uncoiling of fresh towel from the coil.

20. In a towel cabinet, means therein for supporting a coil of fresh towel, an opening in the cabinet through which the towel is accessible to a user, a sliding door normally closing said opening, means including a manually operable member for raising said door and drawing fresh towel 15 from said coil past said opening, a gripper carried 20 on said door and a relatively fixed gripper in said cabinet adapted to cooperate with said first mentioned gripper when the door is raised, to prevent further uncoiling of fresh towel from the coil.

ANDREW FALK.
